UNITED STATES PATENT OFFICE.

THOMAS J. CROSBY, OF ST. LOUIS, MISSOURI.

COVER-FASTENER FOR SHIPPING-RECEPACLES.

1,161,927.

Specification of Letters Patent. Patented Nov. 30, 1915.

Application filed February 7, 1914. Serial No. 817,180.

To all whom it may concern:

Be it known that I, THOMAS J. CROSBY, a citizen of the United States, and a resident of the city of St. Louis and State of Missouri, have invented a new and useful Improvement in Cover-Fasteners for Shipping-Receptacles, of which the following is a specification.

My invention relates to cover fasteners for receptacles, particularly to cover fasteners for shipping receptacles intended for uses which require that the contents of the receptacle can be readily inspected.

The invention has for its objects to make a simple, cheap and durable fastening device for the covers of receptacles which will enable the cover to be easily and quickly removed; and to attain certain advantages which will be more fully set forth herein-after.

The invention consists in the parts, and in the arrangements and combinations of parts as will more fully appear hereinafter.

In the accompanying drawing, which forms part of the specification, and in which like reference characters refer to like parts throughout the several views, Figure 1 is a top plan view of a receptacle embodying my invention with parts broken away; Fig. 2 is a side elevation with the upper and lower part of the receptacle in vertical section; Fig. 3 is a bottom plan view of the lid, the locking bars being shown in their locking position; and Fig. 4 is an enlarged fragmentary detail showing a locking bar and its associated catch.

In the construction which I have shown as embodying my invention, the receptacle is formed of a box 1 which is preferably square in cross-section, and has sides 3, a bottom 4 and a removable lid 2. The box 1 shown in the accompanying drawing is designed for the shipment of eggs, and for this purpose the inside of the box is divided into cells or compartments 9. However, the box may be used for the shipment of other articles; and the particular cellular construction shown forms no part of the present invention.

Riveted or otherwise suitably fastened to the middle of each side wall 3 of the box 1 at the top edge is a hook-shaped keeper 10. A plurality of locking bars 11, preferably four in number, are connected together and pivoted upon a rivet 12 passing through the lid 2. The locking bars 11 lie close to the under face of the lid 2, and each locking bar

11 is provided with a guide strap 13 riveted to the lid. The locking bars 11 have upturned ends 14 adapted to engage with the hook-shaped keepers 10. The faces of the keepers 10 and the faces of the upturned ends 14 are slightly beveled (as shown to the best advantage in Fig. 4) to engage tightly with each other when the locking bars 11 are in their locking position. Two of the opposite locking bars 11 are each provided with a pair of adjacent slots 15, and curled around the portion of the locking bar between each pair of slots 15 is the end of a bail-shaped handle 16. The lid 2 has arcuate slots 17 through which the ends of the handle 16 pass. Riveted to one of the locking bars 11 is one end of a leaf spring 18 which carries at its other end a stud 19, having its end slightly rounded. The stud 19 passes through a hole in the locking bar 11, and, when the locking bars are in their locking position, the stud passes through a hole in the lid 2.

To remove the lid 2, the stud 19 is pressed down by one finger and then the handle 16 is twisted to throw the locking bars 11 out of engagement with the keepers 10, whereupon the lid 2 may be lifted. The lid 2 of the box 1 may be readily removed for inspection of the contents of the box and yet is held firmly in position by the locking bars 11 and the keepers 10 when it is locked. The upturned ends 14 of the locking bars 11 engage the hook-shaped keepers 10 and keep the sides 3 of the box from bulging out. When the box is lifted by the handle 16, the weight is supported by the locking bars 11 and the sides 3. The locking bars 11 cannot be pulled endwise out of engagement with the keepers 10 because their upturned ends 14 are hooked under these keepers. The stud 19 positively holds the locking bars 11 in their locking position so that when the lid 2 is locked in place it cannot be removed without proper manipulation.

It is apparent that the cover fastener which I have shown and described may be considerably modified without departing from my invention, and I do not wish, therefore, to be limited to this exact construction.

What I claim is:

1. A cover fastener for boxes comprising a locking bar pivoted to the lid of the box, a bail-shaped handle having its ends pivotally connected to said locking bar on opposite sides of its pivot, a spring carrying a

stud and secured to said locking bar, said stud passing through a hole in said locking bar and being adapted to enter a hole in said lid when said locking bar is in its locking position, and keepers secured to the sides of said box and adapted to be engaged by said locking bar.

2. A cover fastener for angular boxes comprising a locking member pivoted to the lid of the box on the under side thereof to swing horizontally, keepers secured to the sides of said box on the inside at the upper edges thereof and arranged to be engaged by said locking member, a spring-pressed catch for holding said locking member in its locking position, said catch being automatically actuated by moving said locking member to its locking position, and a bail pivotally connected to said locking member for manipulating said locking member and for carrying said box.

3. A cover fastener for flat-topped boxes comprising locking bars pivoted to the lid of the box on the under side thereof to swing horizontally, the end portions of said locking bars being bent upwardly, hook-shaped keepers secured to the sides of said box on the inside thereof and arranged to be engaged by said locking bars, and a flat bail pivotally connected to said locking bars for carrying said box and adapted to rest normally flatwise against said lid.

4. A cover fastener for boxes comprising a locking member consisting of bars arranged at an angle to each other, said locking member being pivoted at its middle to the lid of the box to swing horizontally on the under side thereof, a flat bail-shaped handle pivotally connected at its ends to said locking member on opposite sides of the pivot axis thereof and adapted to rest flat-

wise on said lid, a spring-pressed catch for holding said locking member in its locking position, and keepers secured to the sides of said box and arranged and adapted to be engaged by the bars of said locking member.

5. A fastener for lids of boxes, said fastener comprising a locking bar pivoted to the lid to swing horizontally, said locking bar having a pair of parallel slots therein on each side of the pivot axis thereof, a bail-shaped handle having the ends thereof pivoted to the portions of said locking bar between said slots, a catch located adjacent to said handle for holding said locking bar in its locking position, said catch being automatically actuated by moving said locking bar to its locking position and being releasable by direct pressure thereon, and keepers secured to said box and arranged and adapted to be engaged by said locking bar.

6. A cover fastener for boxes comprising a locking bar pivoted to the lid of said box to swing horizontally, the end portions of said bar being bent upwardly, hook-shaped keepers secured to the sides of said box and arranged to be engaged by said locking bar, the cooperating faces of said upwardly bent end portions of said locking bar and said keepers being beveled, and a flat bail pivotally connected to said locking bar for carrying said box, said bail being adapted for manipulating said locking bar and for carrying the box and being adapted to rest flatwise against the lid when not in use.

Signed at St. Louis, Missouri, this 5th day of February, 1914.

THOMAS J. CROSBY.
